DESIGN FOR A BROOCH OR SIMILAR ARTICLE

Elsa Maria Kafka, New York, N. Y.

Original application December 9, 1941, Serial No. 104,550. Divided and this application January 21, 1943, Serial No. 109,322.

Term of patent 7 years

To all whom it may concern:

Be it known that I, Elsa Maria Kafka, former citizen of Austria, now stateless, residing at New York, in the county of New York and State of New York, have invented a new, original, and ornamental Design for a Brooch or Similar Article, of which the following is a specification, reference being had to the accompanying drawing, forming part thereof.

In the drawing

Fig. 1 is a front view of a brooch showing my new design;

Fig. 2 is a side view thereof.

This is a divisional application of application Ser. No. D-104,550, filed December 9, 1941.

I claim:

The ornamental design for a brooch or similar article, as shown.

ELSA MARIA KAFKA.
